CIGARETTE PACKAGE OPENER AND EXTRACTOR

Angel E. Redondo, Hatboro, Pa.

Application October 25, 1954, Serial No. 464,289

3 Claims. (Cl. 221—208)

The invention relates to new and useful improvements in a package for cigarettes and more particularly a package provided with means for opening one end of the package and extracting one or more cigarettes from the package through the opening.

In my copending application, Serial Number 444,481, filed July 20, 1954, there is shown a package for cigarettes wherein the package includes means for opening one end of the package and means for projecting one or more cigarettes to a limited extent through said opening. An object of the present invention is to improve the extracting means of the prior package by making said extracting means a part of the inner wrapper of the package instead of separate therefrom.

A further object of the invention is to provide a package for cigarettes having an inner foil wrapper and an outer label wrapper wherein the inner foil wrapper is cut and scored so as to provide a section which can be readily separated from the remaining portion of the wrapper and employed as an extractor for projecting one or more cigarettes to a limited extent from the package.

A further object of the invention is to provide an extractor of the above type with means for positively limiting the extent to which the cigarettes are projected from the package.

These and other objects will in part be obvious and will in part be hereinafter more fully disclosed.

In the drawings:

Figure 1 is a perspective view of a package for cigarettes embodying the improvements before the package is opened.

Figure 2 is a view similar to Figure 1 but showing the tearing strip removed, and the end flap which is attached to the detachable cap lifted to a position where the extractor may be pulled from the package.

Figure 3 is a side view of the package with the outer wrappers broken away to show the manner of slitting said wrapper to provide therefrom an extractor for one or more of the cigarettes.

Figure 4 is a view similar to Figure 3 but showing the extractor separated from the main body portion and lifted so as to project the cigarettes to a limited extent from the package.

Figure 5 is a perspective view of the extractor separated from the package and with the end flap raised.

Figure 6 is a top view of the package showing a modified form of folded end flaps and a clip associated with end flaps for opening the end portion of the package.

Figure 7 is a side view of the package with the outer wrappers broken away to show the upper portion of the inner foil wrapper and with the cellophane cap detached and partially raised and the clip connecting the cap to the end flap of the foil wrapper.

The improvements are shown as applied to a package for cigarettes of the usual type. Said package consists of an inner wrapper of foil paper having extensions which form flaps that are folded upon each other to

2

form a closed bottom and a closed top end. The package includes an outer label wrapper which has extensions forming flaps folded to provide a closed bottom. The top end of the label wrapper preferably terminates short of the top end of the foil wrapper. Enclosing the outer and inner wrappers is a cellophane wrapper having extensions forming flaps which are folded to form a closed bottom end and a closed top end, thus sealing the package.

10 Referring more in detail to the drawings the package includes a front side wall 10 and a similar rear side wall parallel thereto. It also includes an end wall 11 and a similar end wall parallel thereto. The side walls are provided with an extension which forms a front side wall 15 flap 12 and a rear side wall flap indicated at 13. There is also an end flap 14 at one end of the package and an end flap 15 at the other end of the package. These extensions and flaps above referred to are formed from the foil inner wrapper. The cellophane wrapper has similar flaps which are folded to form a closed top end and these flaps of the cellophane wrapper are present but are not visible in the drawings. The inner foil wrapper is provided with extensions which form flaps for closing the bottom end of the package.

20 25 The flap 12 is slit along the line b—b so as to provide a flap 12^a which may be lifted with the flap 15 to form an opening at the right hand end of the package as illustrated in Figure 1. The back side flap 13 is also slit along the score line so as to form a flap 13^a that will be lifted with the flap 15.

30 35 In Figures 2 and 5 the end flap 15 is shown as raised to a position in alignment with the end wall 11 of the foil wrapper. The flaps 12^a and 13^a, while lifted in part with the flap 15, are shown as substantially in their closed position for the sake of clearness.

The cellophane wrapper is provided with a tear strip 16 having a finger piece 17 projecting from one end of the strip, which finger piece may be grasped and the strip which extends all the way around the package removed. This will separate the cellophane cap 18 from the body portion of the cellophane wrapper. This cap 18 is shown as secured on its underside to the flap 15 by an adhesive 19 so that when the cap is lifted to the position shown in Figure 2 it will raise the flap 15.

40 45 The usual revenue stamp 20 is attached to the inner foil wrapper and seals the package. The flaps 15, 12^a and 13^a extend beneath the edge of the stamp but can be readily pulled therefrom when the package is opened.

50 55 As shown in Figure 3 the outer wrappers have been broken away so as to expose the inner foil wrapper. Both the front and back sides of the foil wrapper are similarly constructed. Each has a broken slit line 21 which is spaced away from the end wall 11 of the foil wrapper thus setting off the side walls 22 of an extractor. The upper portion of these side walls 22 of the extractor terminate at a cut line 23 which extends from the cut line 21 to the end wall 11. The front and back side walls of the foil wrapper are also slit at intervals along the lines 24. This sets off side walls 25 for the upper portion of the extractor. Said broken cut line 24 extends substantially to the rear wall 11 so as to provide a hinge line 26.

60 65 The flaps 12^a and 13^a are integral with the side walls 25, 25 of the extractor and the flap 15 is integral with the end wall 11 of the inner wrapper and also the back wall of the extractor. The bottom wall 28 of the extractor is formed by cutting the bottom flaps along the line a—a. These flaps of the extractor may, if desirable, be joined together by any suitable adhesive to make a more rigid bottom structure. As noted above, the line 21 is formed by slitting at intervals the front and back side

walls. The same is true of the line 24 while the line 23, both front and back is a full cut line.

When the tear strip has been removed and the cap raised to the position shown in Figure 2 an upward pull on the cap will be transmitted to the flap 15 which is integral with the end wall 11 of the foil wrapper. This is the end wall of the extractor and a pull will separate the extractor from the body of the foil wrapper so that this extractor may be lifted from the container to the position shown in Figure 4.

The upper portion of the extractor may be swung laterally on the hinge line 26 and this will leave one or more of the cigarettes which have been lifted from the package so that they can be better grasped and removed from the package.

The cut line 21 in the foil wrapper provides stops 27. These stops are part of the retained body portion of the foil wrapper and they extend into the extractor inside of the walls 22, 22 thereof and when the extractor is lifted these stops will engage the bottom wall of the extractor and limit any further upward movement of the extractor. It is noted that the foil wrapper fits snugly within the label wrapper and therefore the stops 27 will enter the extractor instead of passing between the portions 22 of the extractor and the label wrapper outside thereof. As shown in Figure 4 the bottom wall of the extractor is in contact with the stops and the cigarettes have been positively limited as to the extent which they are projected by the extractor. It will be noted that after the tear strip has been removed the cap may be lifted and pulled upon by a single motion upwardly and laterally. The end of the package is opened and the cigarettes are projected through said opening by a single continuous pulling action.

In Figure 6 the end flap 15 is shown as folded to closed position first and then the side flaps 12 and 13 are folded onto the end flap 15. The flaps 12 and 13 are cut to form sections 12^a and 13^a which become a part of the extractor as shown in Figure 5. A clip 29 is attached to the end flap 15 and lies beneath the end flaps 12^a and 13^a. When this clip is lifted and pulled upward the flaps 12^a and 13^a will be opened forming an opening through which the cigarettes can be lifted by the extractor. As shown in Figure 7 the clip is formed in two hingedly connected sections one of which is secured to the flap 15 and the other to the cellophane cap 18.

It is noted that applicant's extractor is formed from the inner foil wrapper and that nothing is added to the ordinary cigarette package except a few cut and semi-cut lines to the inner foil wrapper. The cutting of the foil wrapper which is enclosed in the label wrapper and also the cellophane wrapper if used does not weaken the package.

While the improvement has been shown in connection with a package having a cellophane wrapper and a tear strip, it will be readily understood that other ways may be employed in opening the package and that the particular feature to which the improvement relates is the extractor which is made a part of the inner foil wrapper.

It is obvious that many changes may be made in the details of the construction of the extractor without departing from the spirit of the invention set forth in the appended claims:

I claim:

1. A package for cigarettes comprising inner and outer wrappers, said inner wrapper including sides and ends having closure flaps at the top and bottom ends thereof, said top and bottom side flaps being slit at intervals from one side to the other of the wrapper and said sidewalls being slit at intervals from the top to the bottom to provide an extractor for lifting one or more cigarettes from the package, said side walls of the wrapper being slit at

intervals diagonally from the ends of the slits across the top end flaps to one of the end walls intermediate the ends thereof to provide a hinge line for the upper portion of the extractor, said side walls being cut horizontally inward from the hinge line to provide downwardly facing stop shoulders in the retained portion of the side walls, said side walls being slit at intervals from the inner ends of the horizontally cut lines in the wrapper to the ends of the slits in the bottom flaps whereby a pull on the top end flap of the extractor will sever the wrapper between the slits and release the extractor for withdrawing one or more cigarettes from the package.

2. A package for cigarettes comprising inner and outer wrappers, said inner wrapper including sides and ends having closure flaps at the top and bottom ends thereof, said top and bottom side flaps being slit at intervals from one side to the other of the wrapper and said sidewalls being slit at intervals from the top to the bottom to provide an extractor for lifting one or more cigarettes from the package, said side walls of the wrapper being slit at intervals diagonally from the ends of the slits across the top end flaps to one of the end walls intermediate the ends thereof to provide a hinge line for the upper portion of the extractor, said side walls being cut horizontally inward from the hinge line to provide downwardly facing stop shoulders in the retained portion of the side walls, said side walls being slit at intervals from the inner ends of the horizontally cut lines in the wrapper to the ends of the slits in the bottom flaps whereby a pull on the top end flap of the extractor will sever the wrapper between the slits and form an extractor for withdrawing one or more cigarettes from the package, said downwardly facing stop shoulders being adapted to engage the inner face of the bottom end flaps retained on the extractor for limiting the extent of withdrawal of the cigarettes.

3. A package for cigarettes comprising inner and outer wrappers, said inner wrapper including sides and ends having closure flaps at the top and bottom ends thereof, said top and bottom side flaps being slit at intervals from one side to the other of the wrapper and said sidewalls being slit at intervals from the top to the bottom to provide an extractor for lifting one or more cigarettes from the package, said side walls of the wrapper being slit at intervals diagonally from the ends of the slits across the top end flaps to one of the end walls intermediate the ends thereof to provide a hinge line for the upper portion of the extractor, said sidewalls being cut horizontally inward from the hinge line to provide downwardly facing stop shoulders in the retained portion of the side walls, said side walls being slit at intervals from the inner ends of the horizontally cut lines in the wrapper to the ends of the slits in the bottom flaps, said inner and outer wrappers being enclosed in a cellophane wrapper having a tear strip adjacent the upper end thereof, said cellophane wrapper having flaps at the upper end forming with the separate portions of the cellophane wrapper a cap when the tear strip is removed, said cap being secured to the top end flap of the extractor so that a pull on the cap will sever the extractor wrapper between the slits and form an extractor for withdrawing one or more cigarettes from the package.
